ELECTROSTATIC SHIELDS

Oran T. McIlvaine, St. Charles, Ill.

Application September 6, 1955, Serial No. 532,687

3 Claims. (Cl. 313—313)

This application is a continuation-in-part of my prior application filed February 25, 1952, Serial No. 273,181, now abandoned.

This invention relates to improvements in electrostatic shields adapted for use with electron or space discharge tubes, gas lamps, television tubes, etc., to create a fixed or permanent shield or grid bias without the use of voltage or current.

This is an improvement on the electrostatic shields set forth in my prior Patent No. 2,040,753, granted May 12, 1936, which described an electrostatic shield for a gas discharge lamp that has been widely used successfully for many years, especially in the Neon sign industry. However, the shielding effect was obtained in such gas discharge lamps by virtue of the electrons produced from the arc discharge within the lamp.

One object of this invention is to accomplish an electrostatic shielding effect without the use of voltage of any kind.

Another object of the invention is to permanently charge an electrostatic shield made of dielectric material which may be used in conjunction with electrodes and many other uses for obtaining effective shielding thereby without the use of voltage or current.

Still another object of the invention is to provide for a permanent electrostatic shielding effect for many uses, including electron tubes, by permanently charging a suitable plastic or other fusible dielectric material which may be placed in proper relation to the article to be shielded and thereby produce an effective permanent shielding action.

I have discovered that a permanently charged electrostatic shield may be made from a suitable dielectric material which is melted and placed in a strong electrostatic field. If this material is allowed to cool and solidify in the field, the material will have a permanent charge which may be either positive or negative according to the field in which it was placed. If a section of this material is placed near the article to be shielded, it will have a guiding effect and desirable properties such as those which were obtained by the electrostatic shields described in my Patent No. 2,040,753.

Several embodiments of this invention are illustrated in the accompanying drawings in which:

Fig. 1 is a longitudinal section through a portion of a space discharge tube showing the invention applied thereto;

Fig. 2 is a side elevation of a shielded grid for an electronic tube; and

Fig. 3 is a longitudinal section, partly in side elevation, of an oil burner assembly showing the invention applied thereto.

The permanently charged dielectric material suitable for this purpose may be any of the usual plastics, such as synthetic resins, vinyl resin, acrylic resin, acetate or polystyrene, or of glass. Such non-conductors of electric current are capable of being melted and then solidified

or cooled in an electrostatic field. It may be possible to use a ceramic or other such material which will melt at a high temperature, especially for use in high temperature work.

5 The material of the character described above should be softened either to a plastic state or melted to liquid form, and when the molecules thereof are fluid, it is placed in an electrostatic field, transversely of the field, for example, and remains in such field until it has set or hardened into solid form. When so treated, the material will have a permanent electrostatic charge. It can be charged either positive or negative according to the character of the electrostatic field and the direction of the material with respect thereto. The extent of the charge may be varied, as desired, according to the use of the electrostatic shield.

One use of such material is illustrated in Fig. 1 in which an elongated tube having a wall of electromagnetic wave transmissive material, generally designated at 1, forms a part of a space discharge tube filled with a suitable gas, such as Neon, or one of the other inert gases according to the use of the tube. An electrode is indicated at 2, mounted in the tube 1, and supported by a lead wire 3. The electrode 2 is shown as hollow in this example of the invention.

20 The electrostatic shield is indicated at 4 and is mounted in the tube 1 in any suitable manner surrounding the electrode 2. This electrostatic shield 4 is of the character described above, whereby it is permanently charged without requiring any current or voltage for its effectiveness.

25 Where the electrodes are used in space discharge lamps, an intense positive-column discharge always tends to produce what is known as "sputtering" of the electrodes, with consequent blackening of the container walls. The electrostatic shield surrounding the electrode 2 prevents such sputtering on the walls and confines the discharge to the interior of the hollow electrodes, thereby preventing, or at least retarding the blackening of the container. The permanently charged dielectric material of the character described above produces the effect set forth in my prior Patent No. 2,040,753, without the use of voltage or current as was required therein.

30 It has been found that fluorescent lamps often blacken at the ends, resulting in a failure of operation. I have discovered that the incorporation of such electrostatic shields as described herein, around the electrodes of the lamps at the ends thereof, prevents the blackening and prolongs the life of the lamp many times. The shield 5 may be used also in high temperature lamps for the purpose of controlling blackening, as described in my prior Patent No. 2,060,584, granted November 10, 1936.

35 In many types of electron tubes and lamps the grid element or electrode picks up stray electrons and thereby becomes negative, thus retarding the starting of the tube and making it difficult to start. This is especially true with respect to the commercial fluorescent lamps after they have aged somewhat, and in fact, is a common cause for lamp failure. By thus placing a shield of the type described around the electrode, in the same manner as illustrated in Fig. 1, a shield with a positive charge, the arc can be started easily. If, as in the case of Neon signs, a negative shield is needed to prevent the electrode from sputtering, a positive shield of a few volts is used to start the arc instead of the usual high voltage as heretofore required, and as soon as the arc is started, the shield operates as in my former patent, thereby serving both purposes.

40 I also applied this permanently electrostatic shield to a grid of an electron tube, as indicated at 11 in Fig. 2, to give a permanent charge or bias, and thereby eliminating

the "C" battery or grid voltage. The grid can be operated in this manner either negative or positive, as the case may be. The grid 11 is constructed in the usual manner either from a wire coil or of perforated plates, or otherwise, and is then coated with glass, plastic, or other suitable dielectric material, as described above, by dipping in the softened or melted material, which is then charged, as also described above, and the grid will have a permanent charge or bias. This bias can be changed by the input voltage, as in the usual manner of obtaining amplification.

The grid is prepared, as described above, and used in the conventional manner of employing grids in electronic discharge tubes except that the grid having the electrostatic shield coated thereon makes unnecessary the conventional "C" battery. The amount of charge placed on the grid will be determined by the field in which it is placed. For instance, if it be desired to provide a 3-volt negative bias on the tube, this may be provided by a 3-volt charge on the shield material. In like manner, the material can be charged with 10 volts, or other voltage desired, either positively or negatively. Thyratrons often require as much as 20 volts to start the tube, but if constructed with a positively charged grid, such a tube may be started on its operating voltage. This grid, so made, may be used in any place where a battery-charged grid has been used heretofore.

In television, or cathode ray tubes, these electrostatic plates can be used to replace the usual focus coils or permanent magnets, or the conventional electrostatic plates, thereby saving power for the focus coil and making a much lighter assembly, as well as saving appreciably in the amount of wire used, which reduces the cost of the tube.

The degree of bias on the control element is determined by the voltage used in the electrostatic field when making the shield element. For example, if a grid with a 10 volt bias were desired, a field of perhaps 100 volts would be used. If a 20 volt bias were desired, a field of 200 volts would be used. This may be varied according to the material used and the time in the field, but could be determined readily.

In thyratron tubes, a common source of trouble is the requirement for high starting voltage, in many cases requiring several hundred volts to start the operation of the tube, whereas after it has been started, the arc drop is only a few volts, approximately 5 or 10. This is caused by the negative grid effect of the various elements. By using a positive grid prepared with the permanently charged dielectric material, as described above, this trouble would be eliminated. As soon as the tube starts operating, the circuit would supply the proper grid voltage for control.

I have also found these electrostatic shields of this character useful in other fields, as in the oil burner illustrated in Fig. 3. The burner element is shown at 21. The burner element 21 has a nozzle at the discharge end thereof, adapted to spray oil in an outward direction within the combustion chamber within which combustion may take place. In this embodiment as illustrated, the burner element 21 is mounted within a draft tube 22 spaced therefrom for the circulation of air within the draft tube to support combustion.

When the oil is sprayed from the nozzle of the burner element at usual oil burner pressure, or, for instance, at 100 p.s.i., it impinges against the walls of the combustion chamber and is attracted thereto, thus causing carbonizing of the combustion chamber.

I have provided a permanently charged electrostatic shield 23 mounted on the inner wall of the combustion chamber, or portion of the draft tube 22, where the

5 vapor or spray from the nozzle of the burner element 21 otherwise would strike the combustion chamber or burner tube. A negative charge on the shield 23 would cause the droplets of oil to be repelled from the walls of the combustion chamber or burner tube, thus preventing their accumulation thereon and thereby preventing the carbonizing of this portion of the oil burner structure. In most instances the vapor or spray of oil would be charged negatively by the force of oil passing through the nozzle 21, in which event a like charge on the electrostatic shield 23 would cause these particles to be repelled. However, if in any installation the particles should be charged positively, the positive charge may be applied to the shield 23.

10 The repelling of the droplets of oil from the walls of the combustion chamber or of the air tube 22 will cause these to be mixed with the air supplied and thus carried along in the air tube for combustion therein, or in the combustion chamber, without an accumulation of carbon on the adjacent portion of the burner.

15 These electrostatic shields may be used in many other fields, such as air or smoke filters. For instance, a ring of the material may be placed in the tip of a cigarette and will act to trap the tar substance in the smoke and hold it on the ring. A sheet of this material placed in the air passage, or in a vacuum cleaner, will remove the dust from the air without the use of high voltage, nor the expensive, complicated, and hazardous equipment that would be required otherwise.

20 While I have illustrated and described certain embodiments of the invention, it is recognized that other variations and changes may be made therein without departing from the invention, as set forth in the claims.

I claim:

25 1. An electronic discharge lamp comprising an envelope having a wall of electromagnetic wave transmissive material, an electrode mounted within said envelope, and an electrostatic shield substantially surrounding said electrode and positioned between said electrode and said wall in such fashion as to shield said wall from electrode sputtering, said electrostatic shield comprising a dielectric material having a permanent electrostatic charge.

30 2. An electric lamp comprising a closed envelope having a wall of electromagnetic wave transmissive material, an inert gas within said envelope, an electrode mounted within said envelope, and a tubular member of permanently charged dielectric material surrounding said electrode, said tubular member being positioned between said electrode and said wall so as to prevent blackening of said wall.

35 3. In an oil burner, the combination comprising an elongated nozzle for spraying oil, a draft tube concentrically mounted around and spaced from said nozzle, and an elongated tubular member of permanently charged dielectric material mounted in front of said nozzle and between said nozzle and said draft tube to electrostatically repel the oil spray formed when said nozzle is spraying oil, thereby preventing the accumulation of carbon deposits.
